PC

(22) Filed: **Jun. 10, 2011**

CLAIM

(51) **LOC (9) Cl.** **24-02**

I claim the ornamental design for a robot for the elaboration of
lingual archwires, as shown and described.

(52) **U.S. Cl.** **D24/177**

DESCRIPTION

(58) **Field of Classification Search** **D24/176-177,**

D24/180-181; 72/21.4, 293, 295, 372, 376,
72/379.2, 441; 206/368, 63.5; 433/2-3,

433/20, 25, 27, 31, 51, 68, 75-76, 114, 215,
433/24

See application file for complete search history.

FIG. 1 is a front, top perspective view of a robot for the
elaboration of lingual archwires showing my new design;
FIG. 2 is a front elevational view thereof;
FIG. 3 is a back elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The button, plugs and switch are shown in dashed lines for the
purpose of illustration only and form no part of the claimed
design.
